CLAIM

I claim the ornamental design for an animal feeder, as shown and described.

DESCRIPTION

FIG. 1 is an upper front left perspective view of an animal feeder showing my new design;

FIG. 2 is an upper front right perspective view thereof;

FIG. 3 is a lower front left perspective view thereof;

FIG. 4 is a lower front right perspective view thereof;

FIG. 5 is a top plan view thereof;

FIG. 6 is a bottom plan view thereof;

FIG. 7 is a front elevational view thereof;

FIG. 8 is a rear elevational view thereof;

FIG. 9 is a left side elevational view thereof; and,

FIG. 10 is a right side elevational view thereof.
